UNITED STATES PATENT OFFICE.

MICHAEL WILLIAMS, OF MADISON, WISCONSIN.

MOWING-MACHINE.

SPECIFICATION forming part of Letters Patent No. 650,443, dated May 29, 1900.

Application filed December 29, 1899. Serial No. 741,960. (No model.)

To all whom it may concern:

Be it known that I, MICHAEL WILLIAMS, a citizen of the United States, residing at Madison, in the county of Dane and State of Wisconsin, have invented a new and useful Mowing-Machine, of which the following is a specification.

The invention relates to improvements in mowing-machines.

10 One object of the present invention is to improve the construction of mowing-machines, more especially the pitman connection between the reciprocating cutter-bar and the crank-shaft, and to enable the cutter-bar to reciprocate freely without binding at any inclination.

15 A further object of the invention is to arrange the pitman connection so that it will be out of the way and not liable to be injured by 20 obstructions in the path of the mowing-machine.

The invention consists in the construction and novel combination and arrangement of parts hereinafter fully described, illustrated 25 in the accompanying drawings, and pointed out in the claims hereto appended.

In the drawings, Figure 1 is a plan view of a portion of a mowing-machine provided with a pitman connection constructed in accordance with this invention. Fig. 2 is a front elevation of the same. Fig. 3 is a detail perspective view illustrating the construction of the guiding mechanism. Fig. 4 is a transverse sectional view of the same.

30 Like numerals of reference designate corresponding parts in all the figures of the drawings.

1 designates a supporting-frame to which is hinged or coupled a cutting apparatus 2 of 40 any desired construction, comprising a reciprocating cutter-bar 3 and a finger-bar 4. The inner end of the cutter-bar is provided with a perforated ear or lug 5, which is pivotally connected to the outer end of a pitman, and 45 the latter is composed of inner and outer sections 6 and 7, the outer section being preferably about one-fifth the entire length of the pitman. The sections of the pitman are provided at their adjacent ends with a hinge or 50 pivot joint and are adapted to operate when in alinement or when at an angle to each other. The inner end of the pitman is con-

nected with a crank-shaft 8, disposed longitudinally of the machine, at one side thereof, and designed to be geared with the axle or 55 with one of the carrying-wheels. The crank-shaft is preferably provided at its front end with a crank disk or wheel 9, having a wrist-pin 10, to which the inner end 11 of the pitman is connected.

60 The adjacent ends of the sections of the pitman are connected by a pivot 12, passing through a perforation of a depending lug or ear 13 of a slide 14, and the latter reciprocates on a guide 15. The guide 15, which is 65 disposed longitudinally of the pitman at a point above the same, consists of a bracket or plate provided at opposite sides with projecting edges or flanges 16 and having a depending arm or flange which is secured to the adjacent portion of the supporting-frame. The ways 16 may be formed in any suitable manner, and the slide, which is arranged on the upper face of the guide, is provided with inwardly-extending flanges 19, located at the 70 lower face of the slide and forming opposite 75 grooves for the reception of the edges of the guide. By arranging the pitman beneath the slide and the guide it is out of the way and is not liable to be injured by obstructions in 80 the path of the mower. When the crank-shaft is rotated, the slide is reciprocated by the inner section of the pitman, which is located in advance of the depending portion or arm 13 and which communicates motion to the cutter-bar through the outer section of the pitman. The outer section is adapted to oscillate vertically on the pivot of the slide to accommodate itself to the position of the cutting 85 apparatus, which is adapted to adjust itself 90 to the surface of the ground, and there is no liability of the cutter-bar binding through such movement of the cutting apparatus. Any suitable means may be provided for taking up the wear of the parts at the pivotal 95 connection to prevent lost motion.

It will be seen that the pitman connection between the reciprocating cutter-bar and the gearing of the mower-frame is simple and comparatively inexpensive in construction, 100 that it is easily applied to mowers, and that it provides a flexible pitman which is adapted to yield to the movements of the cutting apparatus, whereby the reciprocating cutter-

bar will be prevented from binding. It will also be apparent that by arranging the pitman beneath the projecting or overhanging portion of the slide and the guide it is located 5 out of the way and is not liable to be injured by obstructions in the path of the mower.

What is claimed is—

1. In a machine of the class described, the combination with a supporting-frame, of a 10 driving-crank located at one side of the frame, a cutting apparatus hinged at the opposite side of the frame and adapted to swing upward and downward, a pitman extending entirely across the frame from the driving-crank 15 to the cutting apparatus and composed of the long inner section 6, extending substantially across the frame from the driving-crank to a point near the hinge of the cutting apparatus, and the short outer section pivotally connected 20 to the adjacent end of the inner section and extending beyond the hinged joint of the cutting apparatus to the cutter-bar and pivotally connected with the latter, a slide connected with the pivots of the sections, and a guide 25 mounted on the frame of the mower and receiving the slide, substantially as described.
2. In a machine of the class described, the combination with the frame of a mower, a reciprocating cutter-bar, and a driving-crank, 30 of a guide mounted on the said frame and extending forward or outward therefrom, a pitman passing beneath the guide and connecting the cutter-bar and the crank, and composed of inner and outer sections pivotally connected, adjacent to the inner end of the 35

cutting apparatus, the outer section lying beyond the inner section and a slide arranged on the upper face of the guide and provided with a depending ear or lug pivotally connected with the inner ends of each of the sections of the pitman, by the pivot of the said sections, substantially as described.

3. In a machine of the class described, the combination with a mower-frame, of a reciprocating cutter-bar, and a driving-crank, of a 40 pitman connecting the cutter-bar and the crank and composed of inner and outer sections, pivotally connected adjacent to the inner end of the cutting apparatus, the outer section lying beyond the inner section, a guide 45 mounted on the frame and provided with projecting side edges and extending over the inner ends of the pitman-sections, and a slide arranged on the upper face of the guide and provided at opposite sides with grooves to receive the projecting edges of the guide and having a depending ear, the pivot of the pitman connecting the sections to the ear of the slide, and permitting each of the sections to oscillate vertically independently of the reciprocation of the slide, substantially as described.

In testimony that I claim the foregoing as my own I have hereto affixed my signature in the presence of two witnesses.

MICHAEL WILLIAMS.
